UNITED STATES PATENT OFFICE

MAURICE GOUDARD, OF NEUILLY, FRANCE, ASSIGNOR TO SOCIÉTÉ ANONYME SOLEX,
OF NEUILLY, FRANCE, A SOCIETY OF FRANCE

CARBURETOR

Application filed July 1, 1929, Serial No. 375,021, and in Belgium August 1, 1928.

The present invention relates to carburetors and, more particularly to those of the type provided with a main and a slow speed nozzle.

5 In carburetors provided with a main and a slow speed (or idling) nozzle, it has been a long standing problem to find means for bridging the "gap" in carburation existing between the period when the feed from slow speed nozzle ceases and the feed from the main nozzle begins.

10 One of the objects of the present invention is to provide an improved form of carburetor in which the "gap" in carburation is eliminated.

15 Other objects will appear in the course of the detailed description now to be given with reference to the accompanying drawings in which:—

20 Figs. 1 and 2 show, diagrammatically a carburetor constructed in accordance with the invention at two stages in the opening movement of the throttle valve.

25 Referring to Figs. 1 and 2 of the drawings, there is shown a constant level reservoir 1 provided with a float 2 controlling needle valve 3,—a fuel supply conduit 4 communicating with a fuel source (not shown),—a fuel conduit 5,—a calibrated passage 6, 30 topped by a nozzle 7 which communicates through orifices 8 with a fuel well 9 provided with an air-intake baffle 10,—a cylindrical mixing chamber 12 divided into air-intake portion 11 and fuel outlet portion 13 35 by a butterfly valve pivotally mounted at 16 and having two wing portions 14 and 15,—an auxiliary or slow-speed fuel conduit 17 in series with orifices 8 and terminating in nozzle 18,—an auxiliary mixing chamber 19 terminating in the wall of mixing chamber 12 by an orifice 21 whose upstream edge is slightly downstreamward of a plane passing through the center of axis 16 and at right angles to the longitudinal axis of mixing 40 chamber 12,—and a by-pass auxiliary mixing chamber 22 terminating in an orifice 23 positioned slightly upstreamward with relation to valve wing 15 when the latter is in closed position. The butterfly valve should 45 be positioned so that, in closed position, the

upstream edge of wing 14 covering orifice 21 lies substantially in the transverse plane passing through the center of axis 16, while the corresponding downstream edge of wing 14 covers orifice 21 and lies downstreamward of the said transverse plane.

55 The hereinabove described assembly functions as follows:

Assuming the butterfly valve to be in the position shown in Fig. 1, a slight opening 60 movement of the valve will cause the upstream and downstream edges of wing 14 covering orifice 21 to move away from the wall of mixing chamber 12 by different amounts, the upstream edge remaining substantially 65 tangent to the wall (since it lies in the transverse plane passing through the center of 16), while the downstream edge moves away a relatively considerable distance (since it lies above said transverse plane and has a longer 70 radius). Otherwise expressed, the section included between said downstream edge and the mixing chamber will increase more rapidly than the corresponding section limited 75 by the upstream edge and the mixing chamber wall as the valve opens and the feed of fuel mixture through orifice 21 will therefore at first increase then, when the valve is sufficiently open to bring nozzle 7 into action, decrease. It is at this point that by-pass 22 controlled 80 by wing 15 comes into play to correct the "lag" of nozzle 7, the opening movement of the valve placing orifices 23 on the suction side of the butterfly valve and maintaining the suction on (and the feed from) nozzle 18 85 long enough to fill the gap in carburation that would otherwise exist. It is to be understood, of course, that the sections of passages 19 and 22 must be properly chosen and orifices 21 and 23 positioned exactly as described to obtain the result desired.

What I claim is:—

1. A carburetor comprising a main mixing chamber having a cylindrical wall portion, a main nozzle positioned to feed fuel to said main mixing chamber, a first auxiliary mixing chamber having a terminal orifice in the cylindrical portion of the main mixing chamber, a second auxiliary mixing chamber having one extremity communicating with said

first auxiliary mixing chamber and having a terminal orifice in the cylindrical portion of the main mixing chamber at a point upstreamward with relation to the terminal orifice of the first auxiliary mixing chamber, an auxiliary nozzle positioned to supply fuel to said first and second auxiliary mixing chambers, means for supplying fuel to said main and auxiliary nozzles, and an elliptical valve positioned to simultaneously obstruct the main mixing chamber and the terminal orifice of the first auxiliary mixing chamber, said valve, when in closed position, sloping so that that portion thereof obstructing the terminal orifice of the first auxiliary mixing chamber lies downstreamward with relation to the rest of the valve.

2. A carburetor comprising in combination a main mixing chamber having a cylindrical wall portion, a main nozzle positioned to feed fuel to said main mixing chamber, a first auxiliary mixing chamber having a terminal orifice in the cylindrical portion of the main mixing chamber, a rotatable butterfly valve of elliptical outline positioned in the main mixing chamber so that, in closed position, the edge of one wing thereof obstructs the terminal orifice of the first auxiliary mixing chamber, said valve sloping, when in closed position, so that that portion thereof, obstructing the terminal orifice of the first auxiliary mixing chamber, lies downstreamward with relation to the rest of the valve, a second auxiliary mixing chamber communicating at one extremity with the first auxiliary mixing chamber and having a terminal orifice in the main mixing chamber at a point upstreamward of that wing of the butterfly valve opposite the one controlling the terminal orifice of the first auxiliary mixing chamber when said wings are in closed position, an auxiliary nozzle positioned to feed fuel to said first and second auxiliary mixing chambers, and means for supplying fuel to the main and auxiliary nozzles.

3. A carburetor comprising a main mixing chamber having a cylindrical wall portion, a main nozzle positioned to supply fuel to said main mixing chamber, a first auxiliary mixing chamber having a terminal orifice in the cylindrical portion of said main mixing chamber, a rotatable, butterfly valve of elliptical outline positioned in the main mixing chamber so that, in closed position, the edge of one wing of said butterfly valve obstructs the terminal orifice of the first auxiliary mixing chamber, said valve having its axis positioned so that a plane therethrough perpendicular to the longitudinal axis of the main mixing chamber passes substantially through the upstream edge of the terminal orifice of the first auxiliary mixing chamber, a second auxiliary mixing chamber having one extremity communicating with the first auxiliary mixing chamber and having a ter-

70 minal orifice in the main mixing chamber at a point upstreamward of that wing of the butterfly valve opposite the one controlling the terminal orifice of the first auxiliary mixing chamber when said wings are in closed position, an auxiliary nozzle positioned to feed fuel to the first and second auxiliary mixing chambers, and means for supplying fuel to said main and auxiliary nozzles.

75 In testimony whereof I have signed this specification.

MAURICE GOUDARD.
